UNITED STATES PATENT OFFICE.

OTTO PIOTTER, OF HARBOR BEACH, MICHIGAN.

BEDPOST-HANGER.

1,385,794.

Specification of Letters Patent. Patented July 26, 1921.

Application filed January 17, 1921. Serial No. 437,745.

To all whom it may concern:

Be it known that I, OTTO PIOTTER, a citizen of the United States, residing in the city of Harbor Beach and State of Michigan, have invented new and useful Improvements in Bedpost-Hangers, of which the following is a specification, reference being had to the accompanying drawing.

This invention is a bed post hanger to hold the side rails to the head and foot pieces. The object is to provide a simple and efficient hanger for this purpose by the use of which the bed may be readily set up or knocked down.

In the drawings:

Figure 1 is a perspective sectional detail of a corner of a bed, showing how the side rail is joined to the head piece by the use of the hanger.

Fig. 2 is a side elevation of this hanger.

Fig. 3 is a side elevation of the hanger showing a view perpendicular to that shown in Fig. 2.

Fig. 4 is a top view.

The invention consists of a one piece hanger 1, which is made of a single piece of sheet metal bent to form a half cylinder so

as to leave the trough 2 with sides 3 to engage the bed-post 3, and a depending hook 4 to engage the end rail 5, and a sleeve 6 to engage the side rail 7. A pin 9 may be passed through the sleeve 6 and the inclosed end of the side rail 7 to lock the latter in place. The side rails may be readily taken off the head piece by unhooking the hook 4 from the rail 5; or may be as readily mounted thereon.

While I have herein described a certain specific method of constructing and assembling the elements of my invention, it is understood same may be varied in minor details, not departing from the spirit of my invention as defined in the appended claim.

What I claim to be new and patentable is:

A bed post hanger made of a single piece of metal and embodying side flanges to engage the bed post, a downwardly directed hook to engage the end rail, and a sleeve to engage the side rail.

OTTO PIOTTER.
